UNITED STATES PATENT OFFICE.

ARTHUR F. RANDALL, OF BOSTON, MASSACHUSETTS, ASSIGNOR TO HENRY M. WHITE, OF SAME PLACE.

ADVERTISING MOTOR-VEHICLE.

SPECIFICATION forming part of Letters Patent No. 658,960, dated October 2, 1900.

Application filed March 17, 1899. Serial No. 709,396. (No model.)

To all whom it may concern:

Be it known that I, ARTHUR F. RANDALL, of Boston, in the county of Suffolk and State of Massachusetts, have invented certain new and useful Improvements in Advertising Motor-Vehicles, of which the following is a description sufficiently full, clear, and exact to enable those skilled in the art to which it appertains or with which it is most nearly connected to make and use the same.

This invention has relation to wagons and carriages constructed and equipped for the purpose of displaying advertisements to the public as they are run or driven along streets and roadways.

It is my purpose in carrying out this invention to lay hold upon the so-called "horseless vehicle" or "automobile" and combine therewith movable or shifting advertisements or signs with other advertising devices in such a manner as to make the said advertising means attractive and valuable to a maximum degree.

To these ends my invention consists of a motor-vehicle provided with a body or frame adapted to display advertisements or signs to the public and movable advertising devices capable of being automatically shifted from time to time for the purpose of bringing different advertisements into view and attracting the attention of the public thereto. The shifting or changing of the advertising means or devices is accomplished automatically and by the means which drives the vehicle, all as I will now proceed to set forth in detail.

Reference is to be had to the annexed drawings, and to the letters of reference marked thereon, forming a part of this specification, the same letters designating the same parts or features, as the case may be, wherever they occur.

Of the drawings, Figure 1 is a side view of a motor-vehicle embodying my invention, a portion being represented in section in order to clearly illustrate a way of constructing and a mode of operating the device. Fig. 2 is a transverse sectional view of what is shown in Fig. 1.

In the drawings, *a* designates the running-gear, and *b* the body, of a motor or horseless

vehicle equipped with my invention. Each side of the carriage-body as it is represented herein comprises a centrally-arranged frame *c*, having a rectangular opening therethrough, with an extension *d* at each side of the said frame made in the form of a bottle. There is a panel *e* above the frame *c* and a panel *f* below it. This form of body is not, however, essential, but is portrayed merely for the purpose of showing the designs that may be employed which will render attractive surfaces upon which advertisements may be displayed. In practice I may use mirrors or other things in the sides of the body upon which to paint or trace advertisements and employ other forms besides bottles.

Within the body *b* the motor *g*, of any suitable kind, may be carried, from which motion is imparted to the carriage, as shown or in any other efficient way. From the motor *g* motion is communicated to a short shaft *h*, upon which a bevel-gear *h'* is arranged, which bevel-gear is engaged on opposite sides by the bevel-pinion *i i'*, arranged to turn loosely on the longitudinally and horizontally arranged shaft *j*, carrying the roll *k*, journaled below which is a corresponding roll *l*. On the opposite side of the body, journaled in suitable bearings, are the rolls *k'* and *l'*. The lower rolls are connected with and rotated by belt-and-pulley connections with the upper rolls, and the roll *k'* is driven by a like connection with the roll *k*. (See Fig. 2.) The rolls may be operated in one direction or the other by shifting the clutch *m*, splined on the shaft *j*, so as to connect one bevel-pinion or the other with the said shaft, so as to turn it as the pinion is turned by its engagement with the bevel-gear *h'*. The clutch *m* has a pendulum lever *n* connected with it, which lever is connected with a lever *o* at the front of the carriage-body, the latter lever being in a position to be reached and moved by the motorman sitting on the seat *p*.

The belt *q*, which drives the rollers from the carriage-motor, normally runs loosely over its pulleys, so as not to drive them. It is, however, equipped with a belt-tightening device *r* on the upper end of a lever *s*, connected with a lever *t* in proximity to the motorman's seat *p*.

Sheets *u* of canvas or other material suitable for receiving advertisements thereon are wound on the rolls *k l k' l'*, and the arrangement is such that the advertisements as the 5 sheets are moved may be displayed through the openings in the frame *c*.

The construction and arrangement are such that the motorman upon starting the carriage by moving the lever *o* in the proper direction 10 may connect the pinion *i* or *i'*, as the case may be, with the shaft *j*, so that when the lever *t* is moved to actuate the belt-tightener the sheets on the rolls may be moved to bring a new advertisement into view in the frame 15 *c*, and this may go on intermittently until the sheets are entirely wound upon one roll from the other, and then by moving the lever *o* in the opposite direction the movement of the rolls and sheets will be reversed, displaying 20 the advertisements on the sheets in reverse order. The belt *q* may be tightened intermittently by a cam *v* on the shaft of the lower pulley which drives the belt *q*, the said cam being constructed and arranged to act upon 25 the belt-tightening device *r*, as is shown in Fig. 1.

The form and arrangement of the mechanism for operating the movable advertisements or signs from the vehicle-operating motor 30 may, however, be varied to suit circumstances and peculiar requirements without departing from the nature or spirit of the invention, which in its broad sense contemplates the utilization of the attractive characteristics of the 35 motor-vehicle or horseless carriage in the production of an advertising medium by connecting the motor-vehicle with an advertising contrivance movable in character and actuated in combination with the vehicle-operating 40 means. It is the connection of a motor-vehicle with an advertising medium which when combined substantially as hereinbefore described effects the creation of a new advertising-wagon having properties in virtue of 45 which it attracts to it greater public attention than contrivances for similar purposes as heretofore constructed.

The motor or means for moving the advertisements or signs may be independent of the 50 motor for running the vehicle, so that the signs may be moved and changed when the vehicle is at a standstill. This may be done by disconnecting the chain shown in the drawings from operative connection with the driving-wheels of the vehicle, or the hub *z*⁵ of the sprocket-wheel over which the chain runs

may run loose on its shaft, so that the chain may not be driven by the motor until the clutch part *z*⁴, splined on the shaft, is moved into engagement with the hub *z*⁵ by the upright shifting lever *z*³, as is shown in Fig. 2. The latter lever is adapted to be moved directly by hand, or it may be moved by the motorman or occupant of the seat *p* by the movement of the lever *z*, which actuates the rod *z'* 65 or other suitable operative medium.

Having thus explained the nature of the invention and described a way of constructing and using the same, though without attempting to set forth all of the forms in which it 70 may be made or all of the modes of its use, it is declared that what is claimed is—

1. In a vehicle of the character described, the combination of a motor, suitable connections between the same and the running-gear 75 of the vehicle for propelling the same, traveling display devices, and connections between the latter and the motor for successively exhibiting said devices, provisions existing by virtue of which the vehicle can be propelled 80 by the motor without affecting the display devices and vice versa, and means also to operate the display devices in opposite directions.

2. In a vehicle for displaying advertisements or signs, the combination of the following instrumentalities; viz., a vehicle, a supporting-frame erected upon the same, a plurality of movable surfaces or sheets having advertisements thereon carried by said supporting-frame and visible from the outside of 90 said vehicle, a motor mechanism carried by said vehicle and deriving its power independent of the movement of the vehicle, means to connect said movable surfaces with said motor mechanism to automatically move said surfaces independent of the movement of the said vehicle and in one direction to display the advertisements thereon and to permit said surfaces to be moved in the opposite direction, and means to effect movement of said surfaces in the opposite direction, while said motor mechanism continues to run in the same 95 direction, substantially as described.

In testimony whereof I have signed my 105 name to this specification, in the presence of two subscribing witnesses, this 25th day of February, A. D. 1899.

ARTHUR F. RANDALL.
